UNITED STATES PATENT OFFICE.

JOHN H. BRAMKAMP, OF PORTLAND, OREGON.

ROUNDABOUT.

1,186,966.

Specification of Letters Patent. Patented June 13, 1916.

Application filed October 18, 1915. Serial No. 56,606.

To all whom it may concern:

Be it known that I, JOHN H. BRAMKAMP, a citizen of the United States, residing at Portland, in the county of Multnomah and State of Oregon, have invented a new and useful Improvement in Roundabouts, of which the following is a specification, reference being had to the accompanying drawings.

10 My invention relates to roundabouts or moving amusement apparatus having cars, or other novel means for riding.

The object of my invention is to provide an amusement apparatus of the type described in Letters Patent No. 953,119 heretofore issued to me on March 29, 1910, for an improvement in roundabouts, and particularly for improvements upon and certain novel arrangements adapted to the device 20 described in said patent. I now propose to provide the aforesaid device with cones or frustums upon the platform or table, the former having peculiarly arranged tracks thereon along which the cars shall travel.

25 I attain these objects, as well as other distinct advantages, by the mechanism, construction and arrangement of parts illustrated in the accompanying drawings, which form a part hereof.

30 Figure 1 is a sectional side elevation of the roundabout showing my device arranged thereon in the form of a cone and frustum. Fig. 2 is a sectional side elevation of the roundabout showing my device arranged 35 thereon in the form of frustums.

Like letters and numerals refer to like parts.

A is a socket secured to the earth.

40 B is a shaft, having an integral rounded lower end 3, adapted to rotate in the socket A in an inclined position.

C is a circular table or platform, the center of which is secured upon the upper end of the shaft B. The table is rigidly secured 45 upon the shaft by means of the system of stay braces D. A circular track D' is secured upon the earth at a distance from the lower end of the shaft B which will allow the rim of the table to roll thereon. A circular track 4 is arranged upon the outermost surface of the table C. An outside continuous guard railing 5 is provided on the edge of the table. A car 6 provided with power means to drive it is placed upon the 50 track 4. The car 6 is also provided with track 4. The car 6 is also provided with guide rollers 7 which engage the guard rail-

ing 5. A cone shell 8 is arranged on the table C. The cone shell 8 has an opening 9 in its apex and an interior partition 10 a little below the apex. A helical track 11, 60 having a railing 12, is arranged about the exterior of the cone shell 8, and tubs 13 are placed upon said track. The pitch of the helical track 11 is arranged and fixed with relation to the inclination of the surface of 65 the table C. The cone shell 8 has an inlet 14 in its upper part, through which inlet the track 11 leads at its highest point of elevation. There is also an outlet 14' in the cone shell 8 at its base.

70 Within the cone shell 8 is a second cone shell or more preferably a frustum shell 16, as shown in Fig. 1. A helical track 18 with rail 19 is arranged about the exterior of the frustum 16 in the same direction as that of 75 the track 11. The track 18 joins with the track 11 at the inlet 14 and from there extends to the outlet 14' and there joins the track 11 at its lowest point. The pitch of this track is arranged and fixed in the same 80 manner as that of the track 11.

In Fig. 2 I show an arrangement of the same track upon a frustum 20, as is illustrated upon the cone 8 in Fig. 1. I have varied the arrangement of the frustum 16 of 85 Fig. 1 by placing the same kind of track upon the interior of an inverted inner frustum 23. The outer frustum 20 in Fig. 2 and the table and motor car are similar to what is seen in Fig. 1 except that the track 11 90 leads directly into the exposed track 21 of the inner frustum 23 which track 21 extends in the same direction to the outlet 14' and thence into the track 11. Cars 13' are placed on the track 11 in Fig. 2. The principle involved in the arrangement of the 95 tracks upon the frustums of Fig. 2 is identical with that shown in Fig. 1.

It will now be seen that when my device is assembled in operative position as shown 100 in Fig. 1, with cars or tubs placed upon the tracks, the motor 6 is started. This causes the table C to roll upon the track D'. The rolling movement of the table causes the helical track 11 to move in a manner to 105 impart an upward helical path of travel to a car or tub on the track. This causes all the cars or tubs in that track to travel in their respective order from the surface of the table to the highest point of the 110 track 11, then to enter the track 18 through the inlet 14. From that point the tubs or

cars travel downward in like manner, and in the same direction, on the track 18 until they emerge through an outlet 14' of the cone 8 upon the track 11 and again pursue the same course of travel.

In Fig. 2 it will be observed that a car or tub starting at the lowest point in the track 11 travels upward in the same manner, and, at the highest point, enters upon the track 21 and thence travels downward along said track until it emerges through the outlets 14" and 14' again upon track 11. It will likewise be seen, by reversing the motor car travel, that the travel of the cars upon the tracks as described will be in reverse direction to that indicated by the arrows in the respective figures.

The arrangement of the tracks may be varied without changing the principle of my invention.

The object of the partition 10 and opening 9 of the cone shell 8 of Fig. 1 is to furnish space for lights and the discharge of rockets or other like articles through the opening of the cone, while in motion, and thus provide other amusement and spectacular features.

It should be particularly noted that the helical tracks are arranged entirely with relation to the inclination of the table, and not with respect to the inclination of the cone or frustum. The angle of inclination of the cone shell 8 in a working device, is less than that shown in the drawings to obtain the best results.

Having fully described my device I claim:

1. A roundabout of the character described, comprising a circular table supported in an inclined position by a shaft in its center, a circular track in which the rim of the table rolls while the table is in an inclined position, a cone shell upon the table having a helical track upon its outer surface, the pitch of said track being arranged and fixed with relation to the inclination of the surface of said table, a frustum within said cone shell having a similar track upon its outer surface, said track extending from a connection with the track of the cone shell at its highest point to a connection with the same track at its lowest point, substantially as described.

2. A roundabout of the character described, comprising a circular table supported in an inclined position by a shaft in its center, a circular track in which the rim of the table rolls while the table is in an inclined position, a frustum shell 20 upon the table, said shell having a helical track upon its outer surface, the pitch of said track being arranged and fixed with relation

to the inclination of the surface of said table, an inverted frustum 23 within said frustum 20 having a similar track upon its inner surface, said track extending from a connection with the track of the frustum 20 at its highest point to a connection with the same track at its lowest point, substantially as described.

3. A roundabout of the character described, comprising a circular table supported in an inclined position by a shaft in its center, a circular track in which the rim of the table rolls while the table is in an inclined position, a cone shell upon the table having an opening in its apex, a helical track upon its outer surface, the pitch of said track being arranged and fixed with relation to the inclination of the surface of said table, a frustum within said cone shell having a similar track upon its outer surface, said track extending from a connection with the track of the cone shell at its highest point to a connection with the same track at its lowest point, substantially as described.

4. A roundabout of the character described, comprising a circular table supported in an inclined position by a shaft in its center, a circular track in which the rim of the table rolls while the table is in an inclined position, a cone shell upon the table having a helical track upon its outer surface, the pitch of said track being arranged and fixed with relation to the inclination of the surface of said table, a frustum within said cone shell having a similar track upon its outer surface, said track extending from a connection with the track of the cone shell at its highest point to a connection with the same track at its lowest point, a car upon said tracks arranged to travel along them, substantially as described.

5. A roundabout of the character described, comprising a circular table supported in an inclined position by a shaft in its center, a circular track in which the rim of the table rolls while the table is in an inclined position, a cone shell upon the table having a helical track upon its outer surface, the pitch of said track being arranged and fixed with relation to the inclination of the surface of said table, a frustum within said cone shell having a similar track upon its outer surface, said track extending from a connection with the track of the cone shell at its highest point to a connection with the same track at its lowest point, means to roll said table along its circular rim track, substantially as described.
